COOKER

Max F. Thau, Los Angeles, Calif.

Application April 4, 1938, Serial No. 199,876

7 Claims. (Cl. 53—18)

This invention relates to improvements in cookers.

The general object of the invention is to provide an improved pressure cooker.

5 Another object of the invention is to provide a novel self-basting cooker.

A further object of the invention is to provide novel means for mounting the container of a pressure cooker.

10 Another object of the invention is to provide a novel heat control means for a pressure cooker.

A further object of the invention is to provide a novel closure securing means for a pressure cooker.

15 Other objects and the advantages of this invention will be apparent from the following description taken in connection with the accompanying drawings, wherein:

Fig. 1 is a side elevation of a cooker embodying 20 the features of my invention;

Fig. 2 is a section taken on line 2—2' of Fig. 1;

Fig. 3 is an enlarged fragmentary section showing the housing closure clamp;

Fig. 4 is a fragmentary top plan view showing 25 the clamp disclosed in Fig. 3;

Fig. 5 is a side elevation of the drum;

Fig. 6 is an enlarged fragmentary section showing the drum closure;

Fig. 7 is an enlarged fragmentary detail of the 30 clamp for the drum closure;

Fig. 8 is a fragmentary section taken on line 3—8 of Fig. 7;

Fig. 9 is a fragmentary section taken on line 9—9' of Fig. 2;

35 Fig. 10 is a section taken on line 10—10' of Fig. 1;

Fig. 11 is an enlarged fragmentary central sectional view through the drum and housing;

Fig. 12 is a section taken on line 12—12' of 40 Fig. 1;

Fig. 13 is an enlarged section taken on line 13—13' of Fig. 11;

Fig. 14 is a fragmentary section showing a modified housing clamp; and

45 Fig. 15 is a fragmentary elevation showing the modified closure.

Referring to the drawings by reference characters I have indicated my improved cooker generally at 10. As shown the cooker is mounted on 50 a base 11 and includes a housing 12 which includes a front wall 13, a rear wall 14 and side walls 15 and 16. The housing includes an upper closure 17 which is hinged as at 18 to the housing. The closure 17 is pivotally mounted as at 55 13 to the rear wall 14 and includes clamping

devices 20 (see Figs. 3 and 4) which are pivotally mounted to brackets 21 on the closure. Each device 20 includes a downwardly protruding hook 22 which when closed hooks to a bracket 23 on the front wall 13 of the housing 12. 5

Each clamp device 20 includes an integral outwardly extending handle 24 which is normally urged downwardly by a spring 25. Upon lifting the handles 24 the hooks 22 are disengaged from the bracket 23 and the closure 17 is free to be 10 opened. The front wall 13 of the housing 12 includes openings 26 and 27 on which closures 28 and 29 are pivotally mounted. The closures include catches 30 and 31.

The housing 12 includes a bottom 32 spaced 15 from the base 11 and supported on brackets which are in turn secured to the walls of the housing 12. Mounted on the bottom 32 I provide a burner 34 which is connected by a conduit 35 to an automatic pressure control 36. The valve 36 is connected to a manually controlled valve 37 and the latter valve is connected to a fuel line 38. A fire plate 34' is supported directly above the burner 34 on arms 34" which are in turn secured to the walls of the housing 12. 20

25 The housing includes suitable air vents and a stack (not shown). Mounted below the bottom 32 and in the rear of the closure opening 27 I provide a receptacle 39 which has an opening 40 in alignment with the opening 27 in the wall 30 housing 12. A burner 41 is arranged on the bottom of the receptacle 39 and beneath a container 42 which is mounted on supports 43 which are secured to the sides of the box 39. The container 42 is preferably filled with wood shavings as e.g. 35 hickory shavings. The burner is connected to the fuel line 38 by a conduit 44 which includes a valve 45.

A conduit 46 leads from the receptacle 39 through the side 15 of the housing 12 and upwardly to a T-member 47 which is in turn connected to a horizontal conduit 48 having a valve 49 thereon remote from the T-member 47. The valve 49 is connected to a sleeve 50 by a coupling 51. The sleeve 50 is secured to a collar 52 by a 40 set screw 53. The collar 52 is in turn suitably secured in an aperture 54 in the wall 15 of the housing 12 as by welding. The sleeve 50 includes a central bore 55 in which I arrange a conduit 56. The conduit 56 has the inner end sealed as 50 at 57 and includes lateral discharge apertures 58'. 45

The conduit 56 is connected by a collar 58 to a conduit 59 which has its inner end sealed as at 60 and which includes inlet apertures 59'. 55 The conduit 59 is engaged in a central bore 61 55

in a sleeve 62. On the sleeve 62 I secure a second collar 63 by a set screw 64. The collar 63 is secured as by welding in an aperture 65 in the wall 16 of the housing 12.

5 The bore 61 in the sleeve 62 has an enlarged bore 66 on the outer end thereof in which a safety valve 67 operates. The safety valve includes a valve 68 which coacts with a valve seat 69 located between the bore 61 and the enlarged bore 66. The valve 68 is normally urged against the valve seat 69 by a spring 70 which acts against a closure 71 which is threadedly adjustable in the outer end of the bore 66. The bore 66 is provided with a discharge aperture 72 disposed between the stopper 71 and the valve seat 69.

10 A pressure gauge 73 communicates with the bore 61 being fitted in a threaded aperture 73' in the collar 62. A conduit 74 communicates with the bore 61 through a threaded aperture 74' in the collar 62 and extends downwardly to a three-way valve 75 which includes a discharge outlet 15 76 to the atmosphere. From the valve 75 a conduit 77 extends to the pressure valve 36 which communicates with the conduit 35.

15 Arranged within the housing 12 I provide a drum 78 which includes curved end portions 79 and a cylindrical central section 80. The end portions 79 have central apertures 81 in which are welded as at 82' hubs 82. Each hub 82 includes a central aperture 83 which is enlarged as at 84 to receive anti-friction bearings 85. The sleeves 50 and 62 have reduced portions engaging the inner element of the anti-friction bearings 85.

20 35 Retaining rings are fixed on the outer ends of the hubs 82. Each hub 82 is externally threaded as at 87 to receive a cap 89. Packing material 90 is introduced between the bevelled inner end of the caps 89, the bevelled outer end of the 40 hubs 82 and the outer surface of the collars 50 and 62.

25 45 The outer end of the collar 52 is inwardly bevelled to receive packing 91 which is held in place by a cap 92 which threadedly engages the collar 52.

50 55 The cylindrical central section of the drum 78 includes an opening 93 which is closed by a closure 94 pivotally mounted on a slotted bracket 95. The opening 93 includes an inwardly directed flange 96 against which an inwardly directed flange 97 on the closure 94 may be tightly sealed by clamping members 98 which are pivotally mounted on pins 99 on the cylindrical central section of the drum 78. The clamping members 98 each includes an operating portion 100 which in turn contacts a wedge 101 on the closure member 98 thereby tightly sealing the closure 94 in the opening 93 when turned in one direction.

60 65 The cylindrical central section of the drum 78 includes inwardly directed ribs 102 which catch the meat juices and when the drum is rotated carry the juices upwardly to discharge the juices onto the material being cooked. The drum is provided with a drain plug 103.

70 75 I weld or otherwise secure to the end of the semi-cylindrical end wall 79 of the drum 78 a sprocket 104. A chain 105 extends from the sprocket through an opening 106 in the rear wall 14 and engages a sprocket 107 which is in turn driven through a gear box 108 by a motor 109. The motor 109 is supported on the base 11.

75 Mounted on the conduits 56 and 59 I show collars 110 which are held in place by set screws 111. The collars 110 have pins 112 passing there-

through and also include hooks 113. The pins 112 and hooks 113 serve to support meat, etc.

In order to provide means whereby smoke from the wood chips in the container is led away from the drum I provide a pipe 114 which has a valve 5 115 connected thereto and which is connected to the T-member 47 and thus is connected to the pipe 46. By closing the valve 49 leading to the drum and opening the valve leading to the pipe 114 the smoke will pass to the atmosphere. 10

In operation when the motor 109 is started the drum 78 is rotated. The burners 34 and 41 being ignited the burner 34 heats the outside of the drum 78 while the burner 41 creates smoke from the wood shavings or other material within the 15 container 42. When the valve 49 is open steam or smoke from the container 42 passes through the conduit 56 out through the apertures 56' into the drum 78. The smoke fills the drum and passes from the drum along with the hot gases 20 from the meat being cooked through the apertures 59' into the conduit 59 and bore 51 to the safety valve 67 and through the conduit 74. When the pressure increases, if the valve 75 is open, the flow of gas to the burner 34 will be regulated by the automatic pressure control valve 36. 25

In Figs. 14 and 15 I show a modification of my invention wherein the drum 12' includes an upper part 120 and a lower part 121. The parts have a peripheral rib member thereon which includes a bevelled portion 122 which projects outwardly. A packing 123 is provided between the bevelled portions 122. A clamping member 124 which consists of a plurality of V-shaped blocks 125 is provided. The V-shaped blocks are mounted on a 35 flexible metal band 126 and are separated by spacers 127. The V-shaped blocks are tightened by end members 128 which are engaged by a bolt 129.

30 From the foregoing description it will be apparent that I have invented a novel cooker which is highly efficient for the intended purpose. 40

Having thus described my invention I claim:

1. In a cooker, an outer housing, a cylindrical drum in said housing, means to rotate said drum, 45 means to heat said drum and means to supply smoke to the interior of said drum.

2. In a cooker, an outer housing, a cylindrical drum in said housing, means to mount said drum for rotation, means to heat said drum and means 50 to supply smoke to the interior of said drum, said last mentioned means passing through said mounting means.

3. In a cooker, a housing having a bottom therein, a burner in said housing, a sleeve member at 55 each end of said housing, means to hold said sleeve members in place, a drum disposed within said housing, said drum having end portions, anti-friction members supported on said sleeves, means on said drum engaging said anti-friction members, a conduit on one of said sleeves and having inlets leading to the interior of the drum, and a safety valve on said conduit. 60

4. In a cooker, a housing having a bottom therein, a sleeve member at each end of said housing, 65 means to hold said sleeve member in place, a drum disposed within said housing, said drum having end portions, anti-friction members supported on said sleeves, means on said drum engaging said anti-friction members, a conduit extending from 70 one sleeve and having outlets opening into said drum, a second conduit in the other sleeve, said second conduit having inlets leading to the interior of the second sleeve, a plurality of meat supporting members mounted on said conduits, a 75

sprocket on one of said sleeves, a motor, a second sprocket driven by said motor and a chain connecting said sprockets.

5. In a cooker, a housing having a bottom therein, a burner in said housing, a sleeve member at each end of said housing, means to hold said sleeve members in place, a drum disposed within said housing, said drum having end portions, anti-friction members supported on said sleeves, a hub on each end of said drum engaging said anti-friction members, a container in said housing, a burner for heating said container, a conduit passing from said container to one of said sleeves, a conduit extending from one sleeve and 15 having outlets opening into said drum, a second conduit in the other sleeve, said second conduit having inlets leading to the interior of the other sleeve, and a safety valve on said other sleeve.

6. In a cooker, a housing having a bottom 20 therein, a burner in said housing, a sleeve member at each end of said housing, means to hold said sleeve members in place, a drum disposed within said housing, said drum having end portions, anti-friction members supported on said 25 sleeves, a hub on each end of said drum engaging said anti-friction members, a container in said housing, a burner for heating said container, a conduit passing from said container to one of said sleeves, a conduit extending from said one 30 sleeve and having outlets opening into said drum, a second conduit in the other sleeve, said second

conduit having inlets leading to the interior of the other sleeve, a safety valve on said other sleeve, means to supply fuel to said first mentioned burner, said means including a conduit having a pressure controlled valve therein, and a pipe connecting said other sleeve and said pressure controlled valve. 5

7. In a cooker, a housing having a bottom therein, a heating member in said housing, a sleeve member at each end of said housing, means 10 to hold said sleeve member in place, a drum disposed within said housing, said drum having end portions, anti-friction members supported on said sleeves, means on said drum engaging said anti-friction members, a container in said housing, a burner for heating said container, a conduit passing from said container to one of said sleeves, a conduit extending from said one sleeve and having outlets opening into said drum, a second conduit in the other sleeve, said second conduit having inlets leading from the drum to the interior of the second sleeve, a safety valve on said second conduit, means to supply fuel to said first mentioned burner, said means including a conduit having a pressure valve therein, a pipe connecting said second sleeve and said conduit, a plurality of meat supporting members mounted on said conduits, a sprocket on one of said sleeves, a motor, a second sprocket driven by said motor and a chain connecting said sprockets. 25 30

MAX F. THAU.
